(57) **CLAIM**

The ornamental design for a streetlight, as shown and described.

DESCRIPTION

FIG. 1 is a perspective view of a streetlight showing the claimed design;
FIG. 2 is another perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof;
FIG. 9 is an assembled view for the product thereof; and,
FIG. 10 is a partial enlarged view of FIG. 1 thereof.
The broken lines depict portions of the streetlight that form no part of the claimed design. The broken lines of alternating length in the drawings are for the purpose of illustrating the boundaries of the enlarged fragment shown in FIGS. 1 and 10.
